DESIGN FOR A CAP FOR BURIAL CASKET HANDLES

Stephen Junkunc, Jr., Oak Park, Ill., assignor to Stephen Junkunc, Sr., Oak Park, Ill.

Application July 8, 1938, Serial No. 78,341

Term of patent 14 years

To all whom it may concern:

Be it known that I, Stephen Junkunc, Jr., a citizen of the United States, residing in Oak Park, in the county of Cook and State of Illinois, have invented a new, original, and ornamental Design for Caps for Burial Casket Handles, of which the following is a specification, reference being had to the accompanying drawing, forming part thereof.

I claim:

The ornamental design for a cap for burial casket handles, as shown.

STEPHEN JUNKUNC, JR.
